DESIGN FOR A DRESS

Herbert M. Harris, New York, N. Y.

Application February 10, 1939, Serial No. 82,901

Term of patent 3½ years

To all whom it may concern:

Be it known that I, Herbert M. Harris, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination of the specific dress disclosed of the specific shirring arrangement on the entire blouse portion of the dress as shown.

I claim:

The ornamental design for a dress, substantially as shown and described.

HERBERT M. HARRIS.
